UNITED STATES PATENT OFFICE.

MARK F. MADDEN, OF CHICAGO, ILLINOIS.

REST-PRODUCING STRUCTURE.

1,415,597.

Specification of Letters Patent. Patented May 9, 1922.

Application filed October 19, 1921. Serial No. 508,739.

To all whom it may concern:

Be it known that I, MARK F. MADDEN, a citizen of the United States, residing at Chicago, in the county of Cook and State of Illinois, have invented a new and useful Improvement in Rest-Producing Structures, of which the following is a specification.

As a premise to the following it may be stated that oftentimes a person lying in bed is subjected to more or less discomfort, and oftentimes pain, by reason of the pressing, by the weight of the body, of certain portions thereof, against the mattress portion of the bed, this occurring sometimes because such portions of the patient alone constitute the points of support of the person, sometimes because the pressure is unequally distributed and is exerted to a greater degree on certain portions of the person, and sometimes because pressure to any degree is exerted on certain portions of a person. Thus by way of example, the foot of a person, when lying on its side, presses unequally on the mattress portion of the bed, the pressure being borne by relatively restricted areas of the foot, more particularly the ankle-bone and the side of the ball of an outer toe; also the legs, trunk and head of a person, when lying down, because of the fact that such portions of the person do not extend normally in a plane surface, are subjected to pressure, and certain portions thereof either to the exclusion of, or to a greater degree than, other portions.

It is my primary object to provide for the relieving of persons from discomfort or pain resulting from conditions such as those above stated. In accordance with my invention the means provided for the purpose above stated may be, at least so far as certain portions of the person are concerned, provided either as a structure which is supported on the mattress portion of the bed without attachment to the person, or, and probably preferably in most cases, provided as a casing in the nature of a garment which is secured about the portion, or portions, of the person which it is desired shall cooperate with it.

In the accompanying drawing I have shown the said means as in the nature of a garment, Figure 1 of the drawings showing, by a view in front elevation, a person with the garment embodying my invention applied thereto; Figure 2, a similar view with the garment vertically sectioned; and

Fig. 3 is a detail section on an enlarged scale of a portion of the structure over a supersensitive portion of the body of the wearer.

In the drawing, which is presented by way of example of the manner of practicing my invention, the structure comprises a casing section 3 which may be of any suitable material which is preferably flexible and very soft, as for example silk, which is made to present the body portion 4 at which it surrounds the trunk of the person, leg portions 5 to receive the person's legs, and foot portions 6, which surround the person's feet. The casing 3 contains padding represented at 7, of any suitable soft material, such as that commonly used as the padding for insoles of shoes, but preferably so prepared as to be very fluffy and less liable to become in compact condition, this padding being so disposed in the casing that it will present a cushioning body either to effect the entire relief of any portion, or portions, of the person, as desired, from pressure exerted against such portion, or portions, when the person is lying down, or to effect relief of any portion of a person, of such pressure, to a degree, even to the exclusion of any pressure thereon, less than the pressure normally exerted against such portion, or portions, when the person is lying down. Thus referring to the illustration presented by the drawing, the padding would be provided of such varying thicknesses at different parts of the person, as for example as illustrated at 8 where it extends adjacent the person's waist whereby undesired pressure against the hip-bones is avoided and at 9 where it extends adjacent the knees of the person and at 10 where it extends adjacent the ankle bones, as to fill in the depressions of the body and be relatively thin at the projecting portions thereof, and either wholly remove pressure from the portions of the person desired to be relieved of the pressure as at 14, Fig. 3, or distribute the pressure against the person, as desired.

As regards the provision of the padding for the feet of a person, reference is hereto made to my copending application for United States patent on foot gear which illustrates in a more detailed manner than the accompanying present application, the disposition of the padding material for the person's feet.

The casing 3 may be made up in any desirable way, it being shown as slit along the

front side of the garment as indicated at 11, 12 and 13, cord or tape 14 being shown for securing the garment upon the person, the cord or tape engaging the free edges of the 5 casing at the slotted portions thereof referred to.

It will be understood from the foregoing description that the padding would also extend across the back of the person and if 10 desired across the front portion thereof, and so disposed as to distribute the pressure, as desired, against the person in lying down, either to relieve certain portions of the person entirely from pressure or to effect a 15 distribution of pressure otherwise than occurs normally when a person is lying down.

It will also be understood that the padding structure may be carried up farther than shown in the drawing, even to the extent of 20 extending over the head of the person, to the same general end as hereinbefore explained.

The padding means instead of being provided for application to the person as shown, may be provided as a structure to be laid 25 upon the bed, in flatwise condition, with the padding so disposed that when the person is lying upon it, it will effect a distribution of pressure against the person, otherwise than as normally occurs when a person is 30 lying on a bed. Thus, by way of example, the padding at one marginal side portion of the padding means may be so disposed as to cooperate, in the manner above stated, with the person when lying thereon at one 35 side and the padding at the opposite marginal portion of the padding means be so disposed that it will cooperate with the other side of the person when lying on his side and the padding at the central portion of 40 the padding means so disposed that when the person is lying on his back it will cooperate in the desired manner with this portion of the person.

The padding would be so provided that 45 it will maintain the predetermined position in which it is provided, as by stitching it to the casing 3.

It is desirable that the padding structure at its exterior surface present substantially 50 straight, or plain, side portions as shown in the drawing, so that when the person is lying on a bed the padding structure will extend substantially flatwise against the mattress portion of the bed.

It will be appreciated that by utilizing 55 my invention a person in lying down is rendered more comfortable, particularly where the person has sore spots which would

be subjected to such pressure, normally, as to create discomfort or pain, such, as for example, in the case of rheumatism, bed sores, and foot afflictions.

Where the person is not afflicted with sore spots and where the padding means would be employed merely as a means of 65 distributing the pressure more uniformly over the portions of the person opposing the mattress part of the bed than normally occurs, to render the person comfortable the padding would be so disposed that the 70 pressure against the entire portions of the person opposing the mattress body would be substantially uniformly distributed over such portions.

While I have illustrated and described a 75 particular embodiment of my invention, I do not wish to be understood as intending to limit it thereto as the same may be variously modified and altered without departing from the spirit of my invention.

What I claim as new, and desire to secure by Letters Patent, is:

1. A structure for the purpose set forth comprising a body of padding material having an internal contour to fit portions of the body, an external contour comprising a substantially regular surface adapted to contact uniformly with a flat supporting surface, and means to secure the structure upon the body, whereby undue pressure upon any 90 part is eliminated and bed sores prevented.

2. A structure for the purpose set forth comprising a body of padding material having an internal surface contoured to substantially fit portions of the body, an external contour comprising a regular surface adapted to contact uniformly with a flat supporting surface, said internal surface having a depression opposite a supersensitive spot of the body to largely relieve the 100 pressure thereon, and means to secure the structure upon the body, whereby undue pressure upon any part is eliminated and bed sores are prevented.

3. A rest inducing garment comprising 105 an internal padding having an internal contour adapted to fit the portion of the body upon which the garment is to be worn, and a substantially regular external surface, a casing covering said external surface, and means to secure the garment in place, whereby when the portion of the body wearing the garment is reclining the pressure thereon will be substantially uniform throughout its supported portion.

MARK F. MADDEN.
